DESIGN FOR A LAWN SPRINKLER

Allan C. Hoffman, Milldale, Conn., assignor to Scovill Manufacturing Company, Waterbury, Conn., a corporation of Connecticut

Substituted for abandoned application Serial No. 84,782, May 4, 1939. This application November 30, 1939, Serial No. 88,595

Term of patent 7 years

To all whom it may concern:

Be it known that I, Allan C. Hoffman, a citizen of the United States, residing at Milldale, county of Hartford, State of Connecticut, have invented a new, original, and ornamental Design for Lawn Sprinklers, of which the following is a specification, reference being had to the accompanying drawing, forming part thereof.

Fig. 1 is a perspective view of the lawn sprinkler embodying my new design,

Fig. 2 is a top plan view of the same,

Fig. 3 is a side elevation of the same,

Fig. 4 is a rear view of the sprinkler as it appears from the right side of Fig. 3, and

Fig. 5 is a front view of the same as it appears from the left side of Fig. 3.

The present application is substituted for applicant's abandoned application Ser. No. 84,782, filed May 4, 1939.

I claim:

The ornamental design for a lawn sprinkler, substantially as shown.

ALLAN C. HOFFMAN.
